Primary Examiner—Stella Reid*(74) Attorney, Agent, or Firm*—Nelson Mullins Riley & Scarborough, LLP(57) **CLAIM**

The ornamental design for a baby bottle, substantially as shown and described.

DESCRIPTION

FIG. 1 is a perspective view of a baby bottle, showing our new design;

FIG. 2 is a front elevational view thereof;

FIG. 3 is a front elevational view thereof, with the nipple and cap secured on the threaded top;

FIG. 4 is a rear elevational view as shown in FIG. 1;

FIG. 5 is a right side elevational view thereof;

FIG. 6 is a left side elevational view thereof;

FIG. 7 is a top plan view thereof; and,

FIG. 8 is a bottom plan view thereof.

The broken line showing of the threaded top, nipple and cap is being shown for illustrative purposes only and forming no part of the claimed design.
